Inventor:

George Buchanan.

United States Patent Office.

GEORGE BUCHANAN, OF WASHINGTON, PENNSYLVANIA.

Letters Patent No. 89,021, dated April 20, 1869.

IMPROVEMENT IN DEVICE FOR STEERING SLEDS.

The Schedule referred to in these Letters Patent and making part of the same.

To all whom it may concern:

Be it known that I, GEORGE BUCHANAN, of Washington, in the county of Washington, in the State of Pennsylvania, have invented a new and improved Helm for Children's Sleds; and I do hereby declare that the following is a full and exact description thereof, reference being had to the accompanying drawings, and to the letters of reference marked thereon.

The nature of my invention consists in a sled-runner-shaped movable cutter, to be operated on by means of a rein in the hands of the rider, in the same manner that a horse is guided, right and left.

This rein is also used in pulling the sled up hill. This invention not only guides the sled with ease and precision, but it does so without retarding its speed in the least.

Claim.

The combination and arrangement of the cutter, a T-shaped lever, *b*, and rein *c*, substantially as and for the purpose set forth.

GEO. BUCHANAN.
